(57) **CLAIM**

The ornamental design for a picture frame smartphone case, as shown and described.

DESCRIPTION

FIG. 1 is a front perspective view of a picture frame smartphone case, showing our new design, according to a first embodiment of the new design.

FIG. 2 is a rear perspective view of the picture frame smartphone case, according to the first embodiment.

FIG. 3 is a front elevation view of the picture frame smartphone case, according to the first embodiment.

FIG. 4 is a rear elevation view of the picture frame smartphone case, according to the first embodiment.

FIG. 5 is a top plan view of the picture frame smartphone case, according to the first embodiment.

FIG. 6 is a bottom plan view of the picture frame smartphone case, according to the first embodiment.

FIG. 7 is a side elevation view of the picture frame smartphone case, according to the first embodiment.

FIG. 8 is an opposite side elevation view of the picture frame smartphone case, according to the first embodiment.

FIG. 9 is a rear perspective view of the picture frame smartphone case, depicting a photo being partially inserted into the picture frame smartphone case, according to the first embodiment.

FIG. 10 is a cross-sectional view of the picture frame smartphone case, based on the cross-sectional line 10 depicted in the rear elevation view of FIG. 4, according to the first embodiment.

FIG. 11 is a cross-sectional view of the picture frame smartphone case, based on the cross-sectional line 11 depicted in the rear elevation view of FIG. 4, according to the first embodiment.

FIG. 12 is another rear elevation view of the picture frame smartphone case, showing our new design, according to a second embodiment of the new design.

(Continued)

FIG. 13 is another rear elevation view of the picture frame smartphone case, showing our new design, according to a third embodiment of the new design; and,

FIG. 14 is another rear elevation view of the picture frame smartphone case, showing our new design, according to a fourth embodiment of the new design.

The subject matter shown in broken lines depicts portions of the photo frame smartphone case that form no part of the claimed design.
